UNITED STATES PATENT OFFICE.

HENRY PATTISON, OF ST. JOHN, NEW BRUNSWICK, CANADA.

PRESS.

SPECIFICATION forming part of Letters Patent No. 338,867, dated March 30, 1886.

Application filed June 6, 1885. Serial No. 167,837. (No model.)

To all whom it may concern:

Be it known that I, HENRY PATTISON, a subject of the Queen of Great Britain, residing at St. John, in the county of St. John, Province of New Brunswick, Dominion of Canada, have invented a certain new and useful Improvement in Presses, of which the following is a description sufficiently full, clear, and exact to enable any person skilled in the art or science to which said invention appertains to make and use the same, reference being had to the accompanying drawings, forming part of this specification, in which—

Figure 1 is an isometrical perspective view of my improved press, represented as mounted on the bench and in position for use; Fig. 2, a side elevation of the same, detached from the bench; Fig. 3, a vertical transverse section of the disk or bed-die shown in Fig. 2, detached from its supporting-shaft, showing, also, the blank resting thereon and the retaining ring or binder in place over said blank; Fig. 4, a vertical longitudinal section of the formers or rotary dies, a portion of the shaft on which they are mounted being shown in side elevation; Fig. 5, sectional views of covers made or formed on the press, the covers being represented as inverted; and Fig. 6 enlarged views of the ring or binder used on the disk.

Like letters of reference indicate corresponding parts in the different figures of the drawings.

My invention relates to that class of presses or machines which are employed by tinners in the manufacture of tin or sheet-metal covers for pots, pails, &c.; and it consists in a novel construction and arrangement of the parts, as hereinafter more fully set forth and claimed, the object being to provide a simpler, cheaper, and more effective device of this character than is now in ordinary use.

The nature and operation of the improvement will be readily understood by all conversant with such matters from the following explanation:

In the drawings, A represents the body or bed of the machine, which is adapted to be fastened to the bench B by the screws α .

Mounted at one end of the bed A there is a vertical standard, C, secured thereto by the nut and bolt m , and journaled in said stand-

ard there is a crank-shaft, D, mounted in suitable boxes, fb , and provided with a spring, v , adapted to elevate the inner end of said shaft when the pressure on the same is removed. A vertical standard, E, rendered adjustable by the slot d and nut and bolt x' , is also mounted on said bed, and journaled vertically therein is a shaft, H, carrying at its upper end the horizontally-arranged disk or bed-die K. This disk is dish-shaped or has a cavity on its upper side, being provided therein with a series of rabbets or shoulders, h , corresponding nearly in contour, but obversely, with the cover to be formed. In Fig. 2 this disk is shown as provided with a shoulder or rabbit, j , which may be omitted, if desired. A series of rotary dies or formers, $tlgz$, are fixed on the shaft D, being adapted to work in connection with the disk or die K. A lever, J, provided with a projection, i , has one of its ends jointed to the top of the standard C, and its other provided with a rod, L, which passes downwardly through the bench B, and is connected with the treadle M, the projection i being adapted to engage the box f and force the dies $tlgz$ down onto the disk K when said treadle is depressed, the spring v raising said box and dies when the treadle is released.

Attached to the standard C there is a bracket, k , and mounted on a horizontally-arranged stub-shaft, n , in said bracket there is a small wheel or roller, w , disposed beneath the edge of the disk K, and slightly in front of the die z , the object of said wheel or roller being to support the side or edge of said disk and prevent it from being broken by the pressure of the rotary dies or formers $tlgz$.

A ring or binder, N, of tin, provided with a downwardly-projecting annular flange, a , is employed to keep the blank G, from which the cover is made, in proper position on the disk K, and also to enable said blank to be drawn in from the outer edges toward the center of said disk when pressure is applied and the dies are revolved to force the blank down into the cavity of the bed-die, the lubricious nature of the tin permitting the blank to slip readily under the ring. The ring N also serves as a cushion to prevent the die or dies on the shaft D from injuring the blank or cover as it lies between the face of said die or dies and the

metal from which the cover is made when pressure is brought to bear upon the latter in rolling it into shape.

In the use of my improvement, the treadle 5 M being elevated, the circular tin blank G, from which the cover is to be made, is placed on the disk or bed-die K, the binder or ring N being placed over its edges to keep it in position and prevent it from injury, as described.

10 (See Fig. 3.) The treadle is then depressed and the shaft D turned, causing the dies on said shaft to press on the blank G and force it into the disk or bed-die K, thereby forming the cover in a manner which will be readily obvious without a more explicit description.

The edges of the shoulders or rabbets h in the face of the disk K are angular, but the edges or peripheries of the dies t l g on the shaft D are slightly rounded, so that said last-20 named dies do not press the sheet-metal blank G into the bed-die to make it conform precisely with said rabbets, but bend it in curves over them, as shown at y, thereby preventing the sheet from cracking or breaking under the

25 pressure to which it is subjected and making a more desirable cover. By not bringing all parts of the sheet into contact with the bed-die the cover is also prevented from being as badly scarred or scratched as it would be if

30 pressed into the angles of the rabbets h.

A shoulder or rabbet, j, is formed near the outer edge or periphery of the disk K, the die z being adapted to press the edge of the blank or circular sheet of metal G, from which the 35 cover is formed, into the same, and thereby produce a cover having a downwardly-projecting annular flange, r, and rim p, the flange being adapted to pass down inside the top of the pot or other vessel on which the cover is 40 used, and thus keep the cover in position on the vessel, this feature of the invention being deemed of especial value in machines of this character.

It will be obvious that one or more dies may be employed on the shaft D, and that the bed-die and also the dies or formers on said shaft are designed to be changed to correspond with the work to be performed or style of cover to be made, several of the different styles for which the machine is adapted being shown in 45 Fig. 5.

Having thus explained my invention, what I claim is—

1. In a press for making covers substantially such as described, the bed A, provided with the standards C E, the shaft H, provided with the disk K, the shaft D, provided with the dies t l g z, the vertically-movable boxes f and b, for supporting said shaft D, the lever J, provided with the rod L and treadle N, and 55 the spring v, combined and arranged to operate substantially as set forth.

2. The disk K, provided with the rabbet or shoulder j, in combination with the dies g z, shafts H D, and means for rotating and exerting pressure on said dies, substantially as described. 65

3. In a press substantially such as described, the roller or wheel w, in combination with the shaft H, disk K, shaft D, and a circular die or 70 dies on said last-named shaft, substantially as and for the purpose set forth.

4. In a press substantially such as described, the ring N, having annular downwardly-extending flange a, in combination with the bed-die or disk K, for preventing the die or dies on the shaft D from injuring the blank or cover and to permit it to be drawn toward the center of the die K as it is formed, substantially as described. 75

HENRY PATTISON.
